EDGE ATTACHMENT FOR A CARPENTER'S SQUARE OR THE LIKE

William E. Darlington, Granada Hills, Calif., assignor to
F.P.I. Inc., North Hollywood, Calif.

Filed May 7, 1973, Ser. No. 357,825

Term of patent 14 years

Int. Cl. D10—99

U.S. Cl. D52—6 A

FIG. 1 is a top and front perspective view of an edge attachment for a carpenter's square or the like showing my new design;

FIG. 2 is a right end elevational view thereof;

FIG. 3 is a front elevational view thereof;

FIG. 4 is a top plan view thereof;

FIG. 5 is a rear elevational view thereof;

FIG. 6 is a bottom view thereof.

I claim:

The ornamental design for an edge attachment for a carpenter's square or the like, substantially as shown.
